(57) CLAIM

The ornamental design for a hairbrush and cover combination, as shown and described.

DESCRIPTION

FIG. 1 is a front perspective view of a hairbrush and cover combination showing our new design;

FIG. 2 is a bottom view thereof;

FIG. 3 is a side view thereof, the opposite side being identical;

FIG. 4 is a rear view thereof;

FIG. 5 is a top view thereof;

FIG. 6 is an exploded perspective view thereof; and,

FIG. 7 is a bottom view of the hairbrush shown separately for clarity of illustration only.

The features illustrated in broken lines form no part of the claimed design.
